HOUSING UNIT

Henry Otis Chapman, Cedarhurst, and Randolph
Evans, Bronxville, N. Y.

Application April 26, 1943, Serial No. 484,552

2 Claims. (Cl. 20—2)

The present invention relates to building structures and embodies, more specifically, an improved structural unit adapted for use as an integral part of a building such as a small home.

The common practice in the building industry has been to construct a house "on the job" by assembling and building the various component parts on the site. This requires a high degree of individual skill on the part of many types of artisans and, likewise, a convenient source of raw materials of many types and of a great variety of equipment such, for example, as kitchen and bathroom accessories. This method of building has always caused the cost thereof to be high, and it is generally recognized that, as a result of the high cost of building, relatively few homes have been built and the standard of housing is comparatively low.

In order to overcome the disadvantages above mentioned, it has heretofore been suggested to prefabricate certain sections of the building such, for example, as the walls and ceilings, but this has not overcome the principal objection above mentioned, inasmuch as the general structure of a house is one which usually follows the environmental or geographical type of design for houses in the locality where the house is to be built and the artisans in that locality have the necessary materials conveniently at hand and are skillful at constructing the particular design selected. The chief difficulty and expense lie in the plumbing and other mechanical equipment that must be incorporated into the building structure, and it is in this respect that the present invention is of unique importance.

An object of the invention, accordingly, is to provide a building unit in which the dominant or principal portion of the plumbing and other mechanical equipment is embodied in a unitary structure.

A further object of the invention is to provide an integral building unit in which the kitchen and bathroom facilities are formed as a unitary structure and adapted to be conveniently related to the remaining portion of the house of which it is to form a component part.

Yet another object of the invention is to provide a building unit of the above character wherein the elements of the kitchen and bathroom are so designed and integrated as to reduce the total height of the building unit to a minimum and enable the elements thereof to be conveniently related to a single floor of a building structure with which the unit is to be associated.

Further objects of the invention will appear

as it is described in greater detail in connection with the accompanying drawing, wherein

Fig. 1 is a view in vertical section taken on a plane passing diagonally through the building unit from corner to corner, as illustrated by the line 1—1 of Fig. 2, and looking in the direction of the arrows;

Fig. 2 is a view in horizontal section, taken on the line 2—2 of Fig. 1, and looking in the direction of the arrows;

Fig. 3 is a view in horizontal section taken on the line 3—3 of Fig. 1 and looking in the direction of the arrows;

Fig. 4 is a view in section taken on the line 4—4 of Fig. 1 and looking in the direction of the arrows; and

Fig. 5 is an enlarged partial view of the wall structure adjacent the lavatory shown in Fig. 2.

Referring to the above drawing, the building unit will be seen to consist of a bottom 10 and a top 11. Side walls 12, 13, 14, and 15 are shown as of equal length, thus making the unit square in cross-section although, if desired, the unit may have other geometrical proportions.

The side walls 12, 13, 14, and 15 are preferably formed of metal which may be stamped and secured as by welding or other convenient securing means in order to afford the desired rigidity and housing facilities hereinafter mentioned.

The walls 12, 13, 14, and 15 are also formed with inner and outer sides between which suitable insulating material is placed and, in order to provide for the necessary plumbing facilities, a soil pipe 16 is provided in one corner of the unit to take advantage of the space there afforded between the inner and outer wall plates.

In the unit illustrated, it will be seen that there is included a cellar or basement portion shown in Fig. 4, access to which is had by means of stairs 17 and including a space 18 into which suitable air conditioning or other heating equipment may be installed, a furnace 19, a recess 20 for laundry tubs, and a space 21 for a washing machine. The stairs 17 communicate with the adjacent basement portion of the building by means of which access is had to the related elements just described.

The kitchen section of the unit is illustrated in Fig. 3 and includes a floor 22 giving access to the stairs 17 and also to a staircase 23 by means of which convenient access may be had to the adjacent floor 24 of the remaining portion of the building. An exterior doorway 25 provided with a door 26 gives access to the exterior of the

unit and building, the unit being designed so that the doorway 25 and its door sill are not below the ground level.

Immediately above the furnace 19 a stove or range 27 is provided in the kitchen, a hot water tank 28 being provided in the corner of the unit and conveniently associated with the range and boiler or furnace 19. A vertical flue 29 is formed in the side wall 15 for the furnace 19 and a duct 30 in the wall 12 for use in connection with the ventilation of the kitchen.

Also provided in the kitchen is a sink 31 beneath which a cupboard 32 is situated and above which an additional cupboard 34 is formed. Above the stove 27 a deep shelf 35 is provided, the shelf being accessible from the adjacent building structure through an aperture 36. In this fashion, food and equipment may be placed upon the shelf 35 and removed therefrom through the opening 36 by a person standing on the floor 24.

The kitchen is also provided with a refrigerator 37, the cooling unit of which may be housed within a cabinet 38, an upper compartment 39 being provided and access to which may be had through a door 40. The refrigerator door is illustrated at 41 and the cooling unit door at 42.

The wall 12 is also formed with a recess 43 having shelves 44, access to which is had from outside the unit and by persons on the floor 24.

The ceiling of the kitchen, which also forms the floor of the bathroom, is shown at 45, the bathroom being illustrated in the sectional view of Fig. 2 and being accessible from the floor 24 by means of a staircase 46. A bath tub 47 is provided between the walls 12 and 15, a towel cabinet being formed at 48 and more remotely in the corner. A lavatory 49 is provided adjacent the bath tub and is formed with a base wall 50 which is located above the doorway 25 and thus provides clearance to permit the door 26 to swing inwardly. The space beneath the lavatory 49 thus provides head room for the stairway. This is necessary in view of the position of the sill of the door 25 with respect to the kitchen floor 22.

Side walls 51 and rear walls 52 are stamped with curved surfaces to provide recesses 53 within which electric lights 54 are received. A medicine chest 55 is provided in the rear walls 52 and a compartment 56 is provided within which ventilating equipment may be installed.

The toilet is provided at 57 and is connected to the soil line 16 in the usual fashion.

The usual plumbing facilities, such as faucets, pipes, waste lines, shower head, etc., are provided for the equipment previously mentioned and a window 57' is provided in the bathroom in the wall 13.

It is also proposed to provide a switch and fuse box 58 in the basement of the building unit, this box having electrical connections with outlets 59 suitably located in the walls 12 and 14, by means of which electrical connections may be had with the adjacent portions of the building of which the building unit forms an integral part. Moreover, heat and air conditioning ducts 60 may be provided in the unit to facilitate the heating of the unit and adjacent structure.

While the invention has been described with specific reference to the building unit illustrated in the accompanying drawings, it is not to be limited save as defined in the appended claims.

We claim:

1. A structural unit for installation in a building comprising a top, a bottom, a plurality of side walls, a floor between the top and the bottom forming two rooms within the sides, one superimposed over the other, said floor being cut away adjacent one side wall to provide head room, a lavatory in the upper room overlying the cutaway portion of the floor, a wall section between the lavatory and said floor to conceal the cutaway portion, a staircase in the lower room beneath the cutaway portion and a doorway and door in the said one side wall between the lower room and the exterior of the unit and having their lower edges disposed at a level between the floors of said rooms.

2. A prefabricated, transportable building unit, adapted to be incorporated into a building having a basement including a floor, a first floor, and a ceiling spaced from said first floor; comprising a bottom, a top and a plurality of side walls, transverse floors extending between said side walls providing a basement space of less height than the spacing between the basement floor and said first floor, and vertically superposed spaces for a kitchen and a bathroom, of substantially equal height, the overall height of said unit not greatly exceeding the distance between said basement floor and said ceiling whereby said first floor is disposed between said transverse floors, stairways wholly within said unit opening through the side walls of said spaces and terminating in alignment with said first floor of said building and with the floors of said respective spaces, and another stairway in said unit extending through said basement space and communicating with said kitchen space and said basement through openings in the transverse floor of said kitchen space and a side wall, respectively.
